UNITED STATES PATENT OFFICE

CLIFFORD SPITAL, OF BIRMINGHAM, ENGLAND

WASHBASIN APPLIANCE

Application filed September 5, 1929, Serial No. 390,564, and in Great Britain December 22, 1928.

This invention relates to a wash basin appliance of the kind having a tank for containing a supply of water and a basin adapted for use as a wash basin.

5 In apparatus of this kind as at present employed it is usual to place the tank at a higher level than the basin so that a gravity feed for the water can be obtained. With this arrangement, however, the tank when in 10 use must be disposed at the back or to one side of the basin, with the result that the apparatus usually occupies an inconvenient amount of space, particularly when it is intended to be used upon vehicles or any other 15 confined spaces.

The primary object of the present invention is to provide an improved wash basin appliance which will be more compact than those hitherto constructed, and which consequently will be particularly suitable for use 20 upon a vehicle. For instance, the appliance constructed in accordance with the present invention lends itself for application to the running board of a motor road vehicle, in 25 which position the available space is very limited.

Referring to the drawings:—

Figure 1 is a perspective view of one form 30 of apparatus constructed according to this invention;

Figure 2 is a transverse sectional elevation of the same;

Figure 3 is a part cross sectional elevation of the same taken on a diagonal line;

35 Figure 4 is a part plan showing a detail of the apparatus;

Figure 5 is an inverted plan of the bottom of the pump employed in the apparatus, and

40 Figure 6 is a section of a detail of the apparatus.

In the construction of apparatus illustrated in the drawings, there is provided a tank 1 of a box-like form having substantially flat sides, and proportioned so that it forms a 45 body like a cube with its vertical corners thereof rounded.

The tank 1 is provided with a top 3 having a depression 4, which may be part spherical, and which constitutes a basin. The part 50 3 slopes down to the depression 4 so that any

water splashing on to this part will flow into the basin.

The tank 1 in plan is substantially square, while the depression 4 forming the basin is preferably circular, thus leaving four corner 55 portions 5, one of which is used for housing a pump 6, whilst another is used for a filler opening 7. The pump may be constructed as a self-contained unit adapted to be secured to the top 3. The latter is provided with an 60 opening 8 and a depending flange 9 internally screw threaded and adapted to receive an externally screw threaded boss 10, from which depends the barrel 11 of the pump 6.

A foraminated stop plate 12 is fixed across 65 the upper end of the barrel 11.

The upper end of the barrel of the pump is closed by a hood 13 having a laterally projecting portion 14 (Figures 3 and 4) and is internally recessed. This hood is secured, detachably or otherwise, to the boss 10. The hood is provided centrally with a stuffing box 15 through which passes a piston rod 16 having a T headed handle 17 fixed to its upper end, and a piston 18 fixed to its lower end. 70 The piston is formed of metal, and is provided with a series of holes 19 adapted to be closed on the upstroke of the piston by a flexible valve 20 retained in position by a nut 21. 75

A non-return valve is provided at the lower 80 end of the pump barrel and comprises an apertured plate 22 fixed across the mouth of the barrel, a flexible valve 23 adapted to close the apertures in the plate 22, and a bolt or the equivalent 24 for securing the valve 23 to the 85 said plate.

The lower end of the tank is closed by a suitable bottom plate 25, which may be strengthened in any convenient manner if necessary, and which is provided with two 90 dished parts or depressions 26 into either of which the lower end of the barrel of the pump may project.

The pump barrel 11 terminates at a short distance from the bottom of the depression 26 95 and is provided with a number of semi-circular serrations to facilitate the ingress of liquid from the tank to the pump barrel, and the main object of the depression is to provide means for enabling the tank to be pumped 100

dry; this prevents freezing up in cold weather.

The valves described on the piston of the pump and at the bottom of the pump barrel may be replaced by any other suitable form 5 of non-return valves, which may if desired be spring controlled.

The pump 11 is preferably situated in one of the front corners of the top of the tank 1, while the filler opening 7 is located in the 10 opposite front corner. The pump and filler opening are of the same size so that the positions of the pump and filler cap are interchangeable.

15 The filler opening may be provided with a screw threaded flange to receive a correspondingly screw threaded filler cap 27, and the cap 27 may have a transverse rib 28 to serve as a handle.

20 At the centre or lowest point of the depression 4 forming the basin is connected one end of a tubular outlet 29. This outlet preferably takes the form of a tube secured to the under surface of the part 4 of the tank top by means of a union member 30 rigidly or detachably fixed to the said top.

25 The tube 29 extends downwardly through the tank and projects through the base 25 of the latter, and is provided exteriorly of the tank with the screw threaded portion 31, on which is mounted a nut 32, and this screw threaded portion and the nut serve as a means for fixing the tank to the running board of a vehicle, or to any other structure.

30 The base 25 of the tank is preferably strengthened by a member 33 at the points where the tube 29 passes through it.

35 A plug 34 is provided for closing the upper end of the tube 29 when desired. This plug is attached to the tank by a fine chain 35, or other flexible member.

40 For additionally securing the tank to the running board or other suitable structure, it may be provided at one corner, or in any other suitable position, with a downwardly projecting stud 36 which is screw threaded and provided with a nut 37.

45 The tank is provided with a lid 38, and this lid is of dished or hollow form and is provided with a beaded edge 39 adapted to rest upon a shoulder 40 extending around the tank 1 near its upper edge. The lid 38 is hinged to the rear edge of the tank and for this purpose is provided with one part 41 of the hinge, which is in the form of a strip of metal, secured to the rear edge of the lid and provided with a cylindrical turned-over portion along its lower edge.

50 The rear edge of the tank 1 is provided 55 with a pair of spaced strips 42 of metal, each provided at its upper end with a cylindrical turned-over portion. The cylindrical turned-over portion of the strip 41 of the lid is adapted to be placed between the cylindrical turned-over portions of the strips 42 on the

tank, and a wire or spindle is passed through all these turned-over portions so as to constitute a hinge about which the lid can be turned.

The strips 42 are provided with an extension portion 43, which is doubled upon itself, and is then bent at a right angle so as to form a horizontal part 44 (Figure 2), the outer edge of which is beaded; the members 44 constitute angle strips forming stops. 75

Within the lid is formed a basket 45 which may be made of wire or strip material so that it forms a skeleton basket, or it may be made of solid pressed or similar plates as shown, and the basket is adapted to hold a towel 80 between itself and the inner surface of the lid. On the outer side of this basket is provided a box or compartment 46 for soap, and this box or compartment is open at the top and is provided with an opening 47 extending vertically down its main side and partially across its base so as to allow the soap or other contents of the box to be easily grasped. The box may also be provided with an indented edge. 85

90 A spring catch 48 of any suitable and well-known type may be provided on the tank and adapted to co-operate with an abutment or catch member 49 provided on the lid for retaining the lid in its closed position. 95

In operation the tank 1 is filled with liquid, and this is transferred when required to the basin 4 by withdrawing the piston rod 16 of the pump by means of the handle 17, and then depressing the piston so as to transfer liquid from the lower side of the piston 18 to the upper side thereof through the medium of the apertures 19. On again withdrawing the piston rod 16 the valve 20 closes all the apertures 19 and the liquid above the piston 18 is forced out of the barrel 11 through an opening 50 at the top of the barrel and out through an opening 51 provided in the lateral extension 14 of the hood 13 of the pump into the basin 4. Any suitable quantity of liquid within given limits may be discharged into the basin 4 by reciprocating the piston 18 the requisite number of times. Liquid may be drained from the basin 4 by removing the plug 34 from the outlet opening. 110

115 It should be understood that various modifications may be made in the parts of apparatus according to this invention without departing from the scope of the invention.

120 What I claim then is:

1. A wash basin comprising a storage tank for water, the top of which is provided with a depression forming a basin, a lift pump for transferring liquid from the storage tank to the basin and disposed within the storage tank and supported by the top of the said tank, the top of the storage tank also having a filler opening, a closure member for the filler opening, a dished lid adapted to close over the tank so as to enclose the basin, the 125

upper end of the pump, and the filler opening, and a discharge tube leading from the said basin through the storage tank to the exterior thereof, and serving as a means of securing the wash basin to a support.

2. A portable wash basin comprising a rectangular storage tank, a top for said storage tank having a depression forming a basin which almost extends to the sides of the tank at about the centre of each side, a lift pump for transferring liquid from the storage tank to the basin and disposed within the storage tank and removably supported by the top of the said tank and depending from one corner of the top of the storage tank between the outer edge of the basin and the walls of the tank, the top of the storage tank also having a filler opening located in a corner of said top in a position similar to that occupied by the pump, a closure member for the filler opening, a dished lid adapted to close over the tank so as to enclose the basin, the upper end of the pump, and the filler opening, and a discharge tube leading from the said basin, through the storage tank to the exterior thereof, means for limiting the opening movement of the said lid, and means for holding the lid in a closed position when desired.

3. A wash basin comprising a storage tank for water, the top of which is provided with a depression forming a basin, a lift pump for transferring liquid from the storage tank to the basin and disposed within the storage tank and supported by the top of the said tank, the bottom of the tank having a recess to receive the lower end of the pump, the top of the tank having an opening provided with an internal screw thread, a hood member adapted to close the upper end of the pump barrel and adapted to detachably screw into the said internally threaded opening, the said hood having a projecting part of inverted channel section extending over the edge of said basin and forming a passage and communicating with the interior of the pump barrel and the pump barrel being carried by said hood, the top of the storage tank also having a filler opening, a closure member for the filler opening, a dished lid adapted to close over the tank so as to enclose the basin, the upper end of the pump, and the filler opening, means on and within said lid adapted to carry soap and towel, and a discharge tube leading from the said basin, through the storage tank to the exterior thereof, and means for preventing, when desired, the discharge of liquid from the basin.

4. A wash basin comprising a storage tank for water, the top of which is provided with a depression forming a basin and slopes downwardly towards such basin, a lift pump disposed partially within the tank for pumping water from the storage tank to the basin, and having a valve controlled inlet at its lower end and a discharge opening at its upper end,

the top of said tank having openings adjacent the basin, in one of which the pump is pendently mounted and the other of which serves as a filler opening, a closure cap for said filler opening, the position of said pump and filler cap being interchangeable, the base of the tank having a pair of recesses, into either of which the lower end of the pump can be inserted so that this end is below the level of the main part of the bottom of the tank, said basin having a discharge orifice at its lowest part, a discharge tube communicating with said orifice and adapted to lead the water from the basin through the tank to the exterior of the apparatus, a plug adapted to close said discharge orifice, a dished lid, and pockets carried by said lid for towels and soap.

5. A wash basin comprising a storage tank for water, the top of which is provided with a depression forming a basin and slopes downwardly towards such basin, a lift pump disposed partially within the tank for pumping water from the storage tank to the basin, and having a valve controlled inlet at its lower end and a discharge opening at its upper end, the top of said tank having openings adjacent the basin, in one of which the pump is pendently mounted, and the other of which serves as a filler opening, a closure cap for said filler opening, the position of said pump and filler cap being interchangeable, the base of the tank having a pair of recesses into either of which the lower end of the pump can be inserted so that this end is below the level of the main part of the bottom of the tank, said basin having a discharge orifice at its lowest part, a discharge tube communicating with said orifice and adapted to lead the water from the basin through the tank to the exterior of the apparatus, a plug adapted to close said discharge orifice, a dished hinged lid, pockets carried by said lid for towels and soap, means for limiting the opening movement of the lid, and means for securing the device to a support.

In witness whereof I affix my signature.
